INVENTOR

UNITED STATES PATENT OFFICE.

JOSEPH P. RUTH, JR., OF DENVER, COLORADO.

MANIFOLD-HEATER.

1,388,377

Specification of Letters Patent. Patented Aug. 23, 1921.

Application filed November 20, 1919. Serial No. 339,361.

To all whom it may concern:

Be it known that I, JOSEPH P. RUTH, Jr., a citizen of the United States, residing in the city and county of Denver, State of Colorado, have invented certain new and useful Improvements in Manifold-Heaters; and I do hereby declare the following to be such a full, clear, and exact description of the invention as will enable others skilled in the art to practice the same.

The invention relates to internal combustion engines and more particularly to means for heating the intake manifolds of those used on automobiles.

The object of the invention is to provide a means for quickly vaporizing the gasoline as it passes through the intake manifold to the cylinders of the engine in cold weather. It is well known that it is difficult to start automobile engines in cold weather unless they are kept in warm places, because of the difficulty in vaporizing the fuel so that it will ignite.

Briefly the invention comprises a tray adapted to be secured to or about the intake manifold in a position such that flames from liquid fuel ignited in the tray will come in contact with the manifold and heat the same, whereby gasoline drawn therethrough from the carburetor will be heated sufficiently to properly vaporize for explosion when it reaches the cylinders.

In the drawings forming a part of this specification,

Figure 1 is a cross section of the device taken on line 1—1 of Fig. 3.

Fig. 2 is a cross section taken on line 2—2 of Fig. 4.

Fig. 3 is a plan view.

Fig. 4 is an elevation showing the device in use.

The drawings show the upright portion 8 of an intake manifold leading from a carburetor (not shown) and having the diverging arms 10 leading to the cylinders. The heater comprises a tray having side walls 12 and a bottom 14. The tray has a middle portion 16 which lies in front of the manifold part 8 when in operative position as shown in Fig. 4, and two enlarged end portions 18 which extend beyond the manifold portion 8 and are positioned largely beneath the arms 10 of the manifold.

A neck 20 rises from the rear wall of the middle part 16 of the tray and curves up

over the top of the manifold in the form of a hook as shown, and in the top of this a vertically disposed set screw is placed as at 24, this screw being adapted to bear against the manifold to bind the heater in place. The inner side walls of the enlarged tray portions 18 are provided with engaging faces 26 adapted to bear upon and be drawn up tightly against the under side of the manifold when the set screw 24 is tightened. Thus the heater is firmly held.

To use the heater it is merely necessary to pour into the tray a small quantity of gasoline, alcohol or the like, and touch a match to the same. This fuel will soon burn off leaving the manifold hot enough to vaporize the gasoline drawn through the carburetor sufficiently for explosion.

In order to obtain more efficient combustion of the fuel in the tray, a plurality of upstanding studs 30 are formed on the bottom of the tray and these are drilled at 32. The passages 32 supply an increased amount of air to flames, thereby securing better combustion and more heat.

I claim:

1. In combination, a T-shaped intake manifold, and a heater therefor having open tray-members for fuel underlying the transverse portions of the manifold, said members having means on their upper edges engaging the under sides of said transverse portions, and hooked means overhanging and engaging the top of said manifold whereby the heater is secured thereto.

2. A heater for a T-shaped intake manifold comprising a fuel tray adapted to be positioned adjacent a lower portion of the manifold and a hook-shaped member to overhang and engage the top of the manifold for securing the tray to the manifold.

3. A heater for a T-shaped intake manifold comprising a fuel tray having a portion adapted to be positioned beneath a transverse portion of the manifold and having an upper edge to engage the under side of said transverse portion, and means to overhang and engage the top of the manifold for securing the tray to the manifold.

4. A heater for a T-shaped intake manifold comprising an open tray for fuel, the tray having a portion adapted to lie in front of the vertical portion of the manifold and end portions adapted to lie beneath the transverse parts of the manifold for heating

the same, and a hook to overhang and engage the top of the manifold for securing the tray to the manifold.

5. A heater for a T-shaped intake manifold comprising an open fuel tray, the tray having a middle connecting portion adapted to lie in front of the vertical portion of the manifold and enlarged end portions adapted to lie at the sides of said portion and beneath transverse portions of the manifold, and means to support the tray in operative position.

6. A heater for a T-shaped intake manifold comprising an open fuel tray having a middle portion adapted to lie in front of a portion of the manifold and end portions adapted to lie at the sides of the manifold portion and beneath transverse portions of the manifold, said tray having upper edges 20 adapted to engage the under sides of said transverse portions, and a hook on the tray adapted to engage the top of the manifold.

7. A heater for an intake manifold comprising a fuel tray having a portion adapted to lie beneath a portion of the manifold, the bottom of the tray having an aperture therethrough for supplying air to fuel in the tray remote from the edges of the tray, and means for positioning the tray in operative 25 relation.

8. A heater for an intake manifold comprising a fuel tray having portions adapted

to lie beneath a portion of the manifold, studs in the tray and mounted on the bottom thereof, vertically disposed apertures being 35 formed in said studs for supplying air to fuel in the tray remote from the edges thereof, and a hook-shaped member for mounting the tray on the manifold.

9. A heater for an intake manifold comprising a fuel tray having a portion adapted to lie beneath a portion of the manifold, studs mounted on the bottom of the tray and extending vertically therein, said studs having apertures formed vertically 40 therethrough to supply air to the tray, and means for mounting the tray on the manifold.

10. A manifold heater comprising a tray open at the top and adapted to contain a liquid fuel, and means on the tray to support the same from the manifold and beneath an arm thereof in order to heat the arm.

11. In combination, an intake manifold for internal combustion engines having a transverse arm, an open tray adapted to contain a liquid fuel, said tray being positioned beneath said arm whereby the exterior of the arm may be heated from flames rising from the tray, and means on the tray for supporting the same from said manifold and in said position.

In testimony whereof I affix my signature.

JOS. P. RUTH, Jr.
